GAMES AND AMUSEMENT DEVICE

Filed Dec. 21, 1928

UNITED STATES PATENT OFFICE

MERRITT B. BEADT, OF BROOKLYN, NEW YORK

GAME AND AMUSEMENT DEVICE

Application filed December 21, 1928. Serial No. 327,518.

This invention relates to games or amusement devices involving a fixed game piece in the form of an apertured back board and a movable game piece resiliently coupled with the fixed game piece and movable relatively to said back-board or predetermined sections or areas thereof in the operation of playing the game; and the object of the invention is to provide a device of the class specified, the 10 fixed game piece of which is preferably in the form of movably coupled members to permit the collapsing of said game piece into a comparatively small package, and in the extension of said game piece, one part thereof will 15 assume a vertical or upstanding position; a further object being to provide a game piece which is resiliently coupled with the first named game piece and movable toward the fixed game piece in the operation of playing 20 the game, said movable game piece preferably being of spherical or cylindrical form and being composed of resilient material, but may be of any form and construction; a still further object being to provide means operating in conjunction with the apertured portions of the fixed game piece for adding other characteristics to the game; and with these 25 and other objects in view, the invention consists in a device of the class and for the purpose specified, which is simple in construction, efficient in use, and which is constructed 30 as hereinafter described and claimed.

The invention is fully disclosed in the following specification, of which the accompanying drawing forms a part, in which the separate parts of my improvement are designated by suitable reference characters in each of the views, and in which:—

Fig. 1 is a perspective view of one form of device made according to my invention and indicating the method of its use.

Fig. 2 is a section on the line 2—2 of Fig. 1 on an enlarged scale.

Fig. 3 is a back view of the structure shown 45 in Figs. 1 and 2.

Fig. 4 is a view similar to Fig. 1 but showing a modification.

Fig. 5 is a front and sectional view of another modified form of device which I employ; and,

Fig. 6 is a transverse, sectional view of the structure shown in Fig. 5.

My improved game or amusement device as shown in Figs. 1 to 3 inclusive, consists of a stationary game piece 10 and a movable game piece 11 coupled with one part 12 of the game piece 10 by means of a strong elastic or resilient member 13. In the preferred form of my invention, the game piece 11 is preferably in the form of a hollow rubber ball, the member 13 being retained therein by a washer 14, note Fig. 2 of the drawing. It will be understood however, that any form and construction of movable game piece may be employed and may be made of any desired material.

In the construction shown, the member 13 is coupled with the central portion of the part 12, and this coupling is reinforced by a flexible spring tube 15 which will prevent undue wear upon the member 13 as will be apparent.

The part 12 of the game piece 10 constitutes a base plate or table member which is preferably supported upon cushion leg members 16 in order that the game piece will not mar a table or other surface, or means may be provided for permanently retaining the base-board or part 12 to a suitable support, and in some uses of the device may constitute a table proper.

Movably coupled or hinged to the rear end portion of the part 12 is a part 17 which normally lies in juxtaposition to the part 12 and is adapted to be extended into a vertical or upright position as seen in the several figures, and is retained in its upright position by brace links 18 and 19, the link 18 being pivoted to the part 17, the link 19 pivoted to the part 12, and said links being pivotally coupled as seen at 20. These links may be arranged at one or both sides of the game piece 10.

The part 17 is provided with a plurality of apertures 21, any desired number of which may be employed, and these apertures may be placed in any desired arrangement, it being understood that the front of the part 17 may be characterized in any desired man-

ner to represent games of different kinds and classes.

For example, in a shooting game and assuming the game piece 11 represents a bullet, the apertures 21 may be positioned on predetermined parts of the body of animals of different kinds and classes. Further, the part 17 may represent a golf course, and the game piece 11 a golf ball adapted to pass through the separate holes in a successive order, and numerous other adaptations of the structure disclosed may be made within the scope of my invention. It is preferred that the game pieces 11 are slightly less in diameter or contour than the diameter or contour of the respective apertures 21. On the other hand, a material difference in diameters may be employed as illustrated in the accompanying drawing.

In the operation of playing the game, the game piece 11 is grasped in one hand, and the resilient or elastic member 13 is extended to place the same under tension, and after taking aim, the game piece 11 is released with the intent of passing through a specific aperture 21 in the part 17. In this operation, it is important to agitate or move the game piece 11 vertically to the desired degree prior to releasing the same, this operation being indicated in full and dotted lines in Fig. 1 of the drawing. This agitation or movement brings about the skill and fascination in the operation of playing the game, it being understood that if the game piece 11 is released, without such agitation, it will follow a direct course to the point of its mounting on the part 12, and will not pass through any of the apertures 21.

At this time, it may also be stated, however, that the game may be played on a rebound from the table or base part 12. In other words, it may be necessary to first strike this part prior to passing the ball or game piece 11 through a predetermined aperture.

As previously stated, the several apertures 21 may have different values or characteristics. For example, in Fig. 1, the four apertures shown are valued at 5, 10, 15 and 25 respectively. In addition to such values or characteristics, I may employ in conjunction with the part 17 and cooperating with the respective apertures 21 therein, other game pieces 22 pivotally supported upon a rotatable member 23 which is supported on the crosshead of a U-shaped frame 24 arranged on the rear surface of the part 17 and above each of the apertures 21 therein, as clearly seen in Figs. 2 and 3 of the drawing.

With this construction, it will be apparent that the speed of the ball or game piece 11 in passing through a given aperture 21 will strike the game pieces 22 causing the same to be rotated upon the crosshead of the

U-shaped frame, and when the rotation ceases, one of the several members 22 will remain in view rearwardly of the said aperture, and printed or otherwise fixed to the exposed surfaces of the members 22, may be characters, numerals or other game characteristics. On the other hand, these members 22 may be of a contour to represent animals, beings, objects or things.

In playing the game, each player may take one turn or a predetermined number of turns, depending largely upon the particular nature of the game being played, and the manner of arranging the count or tally.

In Fig. 4 of the drawing, I have shown a slight modification, in which figure, the members 22 have not been illustrated, it being understood however, that said members may be employed. In this construction, instead of coupling one resilient member 13 with the table or base part 12, I employ four of such members 13^a, 13^b, 13^c and 13^d, each carrying at its free end, game pieces 11^a, 11^b, 11^c and 11^d, the inner ends of which are brought to a given point of attachment, preferably centrally of the part 17 as seen at 17^a.

In this type of a game device, it will be an object to pass each game piece 11^a—11^d through each of the four apertures 21 in the part 17 by advancing the game pieces separately. They may however, be advanced collectively. It will also be understood that the plurality of game pieces may be coupled with the part 12 if desired, my invention not being limited to the specific arrangement shown in Fig. 4.

In Figs. 5 and 6 of the drawing, I have shown another modification wherein the game device resembles somewhat the game of skee ball. In this construction, I employ a stationary game piece 25 which consists of a base or table part 26, a movable upstanding part 27 and an adjustable part 28.

The part 28 consists of a forwardly directed arm 28^a having at its front end an upstanding buffer, mound or wall member 29, and the rear end of said arm having an elongated aperture 28^b, in which the shank of a screw 30 is arranged, a nut 31 being employed to clamp the part 28 in firm engagement with the part 26 in the different positions of its adjustment.

The part 27 is hinged or otherwise movably coupled with the part 26 as seen at 32 and consists of a base portion 33 upon which is supported an annular ring 34, within which are two other rings 35 and 36, the ring 35 being supported in connection with the ring 34 by radial bracket members 37, and the ring 36 supported in connection with the ring 35 by other radial brace members 38 in staggered relation to the brace members 37. This forms an openwork structure permitting the free passage of a movable game piece 39, note Fig. 6, through the chambers formed

between the rings 34—35, 35—36 or through the central chamber formed by the ring 36. If desired, one or more small rings 40 may be arranged within the chambers between the rings 34, 35 and 36, one of which is shown at the top of the part 25 and between the rings 34 and 35. In this type of game, the passage of the game piece 39 through the respective chambers will register a score depending upon the values given to said chambers or passages as will be apparent.

The game piece 39 is supported at one end of a resilient, elastic or other member 41 similar to the member 13. Its other end is supported upon the part 26 and reinforced by the spring-like tube 42 similar to the tube 15.

The game shown in Figs. 5 and 6 may be played in the same manner as the game shown in Fig. 1 and without using the adjustable part 28. But, when said part is employed, the object of the game will be to first strike the ball or other game piece 39 against the buffer, mound or obstructing wall 29, prior to passing the same through a given chamber or compartment, the player having the option of adjusting the part 28 by hand to the desired position with reference to the part 27, it being also preferred that the part 29 be pivoted to the part 28 as indicated at 43 in Fig. 6 of the drawing, so that the angular position of the part 29 may be regulated.

In this game, skill will be required in judging the tension applied to the member 41, or in other words, the relative position of the game piece 39 with respect to the member 29 when the latter is in a given position of adjustment.

In the many possible forms of producing my improved game, while the actual play or operation may seem simple, in fact, it requires great skill and accuracy upon the part of the operator to accomplish the desired result, such as, in passing the ball or game piece through a predetermined aperture, compartment or chamber.

While this game is adapted to be commercialized for sale in the home for the amusement of both young and old, in the numerous adaptations thereof, it will also be understood that the same may be constructed as an amusement apparatus for use in amusement parks, resorts, hotels and other public places, as a skill testing device wherein premiums or prizes may be given for the accomplishment of predetermined scores or results by those participating, as in other apparatus of this class.

It will be understood that my invention is not necessarily limited to any of the specific structural features herein shown and described, nor to any particular type or character of game utilizing the distinctive characteristics and features forming the basic principle of this invention, and while I have shown and described certain details of con-

struction, it will be understood that various changes therein and modifications thereof may be made within the scope of the appended claims without departing from the spirit of my invention or sacrificing its advantages.

Having fully described my invention, what I claim as new and desire to secure by Letters Patent, is:

1. A game of the class described comprising a table member, an upstanding body adjacent one end of the table member having a passage extending therethrough, a manually controlled game piece involving a resilient extensible member, one end of which is coupled directly with said table member at a point forwardly of said body and adapted to be advanced for passage through the passage in said body and a wall member adjustably supported in connection with the table member and extending upwardly therefrom and adapted to be extended forwardly with respect thereto and to said body and in connection with which the movable game piece operates.

2. A game of the class described comprising a table member, an upstanding hollow body adjacent one end of the table member, said body being formed by a plurality of annular bands arranged one within the other to form independent annular passages, a manually controlled game piece involving a resilient extensible member, one end of which is coupled directly with the table member and adapted to be advanced in the direction of the upstanding body for passage through the passages therein.

3. A game of the class described comprising a table member, an upstanding hollow body adjacent one end of the table member, said body being formed by a plurality of annular bands arranged one within the other to form independent annular passages, a manually controlled game piece involving a resilient extensible member, one end of which is coupled directly with the table member and adapted to be advanced in the direction of the upstanding body for passage through the passages therein, and an individual ring arranged within one of the annular passages of said body and through which said game piece is adapted to be passed.

4. A game of the class described comprising a table member, an upstanding hollow body adjacent one end of the table member, said body being formed by a plurality of annular bands arranged one within the other to form independent annular passages, a manually controlled game piece involving a resilient extensible member, one end of which is coupled directly with the table member and adapted to be advanced in the direction of the upstanding body for passage through the passages therein, and means on the table member for reinforcing the attachment of the resilient extensible member therewith.

5. A game of the class described comprising a table member, an upstanding hollow body adjacent one end of the table member, said body being formed by a plurality of annular bands arranged one within the other to form independent annular passages, a manually controlled game piece involving a resilient extensible member, one end of which is coupled directly with the table member and adapted to be advanced in the direction of the upstanding body for passage through the passages therein, means on the table member for reinforcing the attachment of the resilient extensible member therewith, and a wall member adjustably supported in connection with the table member and movable relatively to said upstanding body and in connection with which the game piece is adapted to operate.
20. 6. A game of the class described comprising a table member, an upstanding hollow body adjacent one end of the table member, said body being formed by a plurality of annular bands arranged one within the other to form independent annular passages, a manually controlled game piece involving a resilient extensible member, one end of which is coupled directly with the table member and adapted to be advanced in the direction of the upstanding body for passage through the passages therein, means on the table member for reinforcing the attachment of the resilient extensible member therewith, a wall member adjustably supported in connection with the table member and movable relatively to said upstanding body and in connection with which the game piece is adapted to operate, and means for retaining said wall member in different positions of adjustment.
40. In testimony that I claim the foregoing as my invention I have signed my name this 20th day of December, 1928.
